UNITED STATES PATENT OFFICE.

HENRY L. SPIEGEL, OF INDIANAPOLIS, INDIANA, ASSIGNOR TO FRANK W. MIX, OF NEW BRITAIN, CONNECTICUT.

CASE FOR LOCKS.

SPECIFICATION forming part of Letters Patent No. 316,411, dated April 21, 1885.

Application filed April 23, 1883. (No model.)

To all whom it may concern:

Be it known that I, HENRY L. SPIEGEL, a citizen of the United States, residing at Indianapolis, in the county of Marion and State 5 of Indiana, have invented certain new and useful Improvements in Cases for Locks, of which the following is a specification.

My invention relates to an improvement in lock-cases for bureau or desk drawers, or other 10 cabinet-work.

Prior to my invention lock-cases have ordinarily been secured within hand-chiseled mortises by fastening-screws. Owing to the expense in forming hand-chiseled mortises, due 15 to the fact that such work required skilled labor and considerable time for its execution, an attempt had been made to construct a lock that should be adapted for insertion and retention in a machine-made mortise, or one 20 formed by a routing-tool, and thereby materially reduce the expense incurred in fitting and securing the lock in place, as by the employment of suitable machinery, routed lock 25 cavities or mortises could be made at a very much less expense than hand-chiseled mortises. The lock devised with this object in view was provided with a cap-plate having its edges projected or extended laterally beyond the side walls of the lock-case, a front plate 30 with its side edges made flush with the side walls of the lock-case, and a top plate or selvage of a width equal to the thickness of the lock-case. The lock-case thus constructed was driven or forced into a shallow routed cavity, 35 the cap-plate resting in contact with the rear wall thereof and retaining the lock against displacement in one direction, while the laterally-projecting edges of the cap-plate entered the side walls of the routed cavity and prevented 40 the lock from displacement in the opposite direction. As the cap-plate was seated in direct contact with the rear wall of the cavity, the key-post was necessarily cut off or made flush with the outer surface of the cap-plate, 45 no provision having been made for securing the lock-case within a routed cavity provided with a space or recess for the reception of a projecting key-post. In view of the fact that locks constructed with projecting key-posts 50 possessed certain advantages that met the demands of the trade, the peculiar construction

of lock above described with its flush key-post and adapted to be driven into a routed cavity failed of introduction, preference being given to the old form of lock-case with its projecting 55 key-post, though it necessitated the hand-chiseled mortise and fastening-screws for its attachment.

Another improvement in lock-cases is shown and described in Letters Patent No. 241,828, 60 granted to me May 24, 1881. This lock-case is provided with a projecting key-post and a projecting or extended top plate or selvage that covers and conceals the space or recess formed in the mortise for the reception of the 65 projecting key-post. In order that the lock-case in question might be secured within a mortise of such form as would admit of the projecting key-post, the side edges of the cap-plate and front plate were extended laterally 70 beyond the side walls of the lock-case, thereby forming grooves or channels which engaged or interlocked with correspondingly-formed projections or ribs on the side walls of the mortise, and thus retained the lock-case against 75 forward or rearward displacement. The lock-case, being thus secured at its sides, allowed of a space or recess being formed in the rear wall of the mortise and in rear of the cap-plate for the reception of the projecting key-post, which 80 space was covered and concealed from view by the projecting top plate or selvage. While this latter construction of lock possesses valuable features of improvement not disclosed by the prior art, yet the form of lock shown 85 and described in the patent is such as to preclude its adoption for use in routed cavities, because its front plate is not of the proper form to fit within and cover a cavity made by a routing-tool.

The object of this invention is to obviate the objectionable features and defects hereinbefore set forth, and provide a lock-case of such form and construction that it may have a projecting key-post, if so desired, and be secured 95 within a routed cavity, and snugly retained therein, so as to conceal the cavity from view and form a neat and finished appearance when in place.

With these ends in view my invention consists in a lock-case having its edges constructed to engage or interlock with the side walls

of a routed cavity, and provided with a front plate having a rounded bottom adapted to fit within a countersunk recess around the routed cavity and constitute a support for the lock-case and conceal the cavity from view.

5 In the accompanying drawings, Figure 1 is a view in perspective of one form of lock embodying my invention, and Fig 2 is a view in perspective of the routed cavity or mortise 10 within which a lock of the form shown in Fig. 1 is adapted to be inserted.

A designates the cap-plate, the side edges of which project laterally beyond the sides *a a* of the lock-case and form overhanging side walls. 15 Instead of constructing the cap-plate with its edges projecting beyond the sides of the case in the form of thin flanges, other suitable projecting or overhanging forms for the edges or sides of the case may be employed, so long as the 20 same or substantially the same result is accomplished.

B is the front plate, secured to or connected with the side walls, *a a*, of the lock-case, while its lower end or portion extends below the lower edge of the case, and is formed with a semi-circular or rounded bottom. The top plate, *b*, may be formed in one and the same piece with the front plate, B, and bent at right angles thereto in the manner and form usually 25 resorted to.

30 C designates a portion of a drawer-front or other article or support to which the lock is to be applied, and within which is formed by a routing-tool the routed cavity D.

35 The routing-tool or cutter is of proper shape to form a routed cavity with side walls of such shape or configuration that the sides of the lock-case will when inserted interlock therewith, and thereby prevent the displacement of the lock either in a forward or backward direction within the cavity or mortises; also to form a space in the rear wall of the cavity for the admission of a projecting key-post, and also to form the lower portion of the 40 cavity or mortise so that the rounded bottom of the front plate shall fit therein and conceal the cavity from view. The lock being inserted into the routed cavity, the projecting key-post is received within the space formed in 45 the rear wall thereof, while the projecting or overhanging top plate or selvage completely covers the upper portion of the cavity and conceals it from view. The sides of the lock-case engage and interlock with the side walls 50 of the routed cavity and thereby prevent the lock-case from either forward or rearward dis-

placement. The rounded bottom of the downwardly extended front plate fits within a countersunk recess and serves to form a neat and finished appearance on the inner side of the 55 drawer-front by concealing the routed cavity from view, and also serves as a vertical support for the lock-case.

From the foregoing it will be observed that while my improved lock-case is adapted to be 60 secured with a routed cavity, and hence may be applied at very slight expense, it has embodied therein such features of form and construction as are deemed of value and importance by the trade to insure the best practicable 65 form of lock and the desired neatness of finish in its application.

Having fully described my invention, what I claim as new, and desire to secure by Letters Patent, is—

75 1. A lock-case having a front plate formed with a rounded bottom, a cap-plate forming in connection with the front plate intervening spaces or grooves on the opposite edges of the lock-case, and a top plate extending over and beyond the cap-plate, the projecting edges of the front plate being adapted to fit within a countersunk recess around the routed cavity within which the lock-case is inserted, substantially as set forth.

80 2. A lock-case having a front plate formed with a rounded bottom, a cap-plate secured to or connected with the front plate and constructed to form therewith intervening spaces or grooves on opposite edges of the lock-case, 85 and a top plate extending over and beyond the cap-plate, in combination with a support having a routed cavity provided with a countersunk recess adapted to receive the outer and projecting edges of the front plate, substantially as set forth.

90 3. A lock-case having a front plate formed with a rounded bottom, a cap-plate secured to or connected with the front plate and constructed to form therewith intervening spaces 95 or grooves on opposite edges of the lock-case to retain it in place within the routed cavity, and a top plate extending over and beyond the cap-plate, in combination with a support provided with a routed cavity of a depth sufficient to receive the projecting edge of the top plate flush therein, substantially as set forth.
